UNITED STATES PATENT OFFICE.

EDWARD J. MANSER, OF NOBEL, ONTARIO, CANADA.

ACID-STILL.

1,320,080.

Specification of Letters Patent.

Patented Oct. 28, 1919.

Application filed May 31, 1919. Serial No. 301,132.

To all whom it may concern:

Be it known that I, EDWARD J. MANSER, of Nobel, in the district of Parry Sound, Province of Ontario, Canada, have invented 5 certain new and useful Improvements in Acid-Stills, of which the following is a specification.

This invention relates particularly to stills in which sodium nitrate (chilli salt-peter) is subjected to the action of sulfuric acid in the process of manufacturing nitric acid. Such stills are usually made of cast iron and are liable to crack owing to the difficulty experienced in properly intermingling the acid and salt-peter which results in a large dry area persisting at the bottom of the still until late in the process. The imperfect mixing of the acid and salt-peter also makes the process slower than is theoretically practicable and results sometimes in almost explosive reactions when the acid suddenly penetrates a previously dry part of the salt-peter.

My object therefore is to devise means for 25 overcoming the troubles just referred to. I attain my object by means of the constructions hereinafter described and illustrated in the accompanying drawings in which—

30 Figure 1 is a vertical section, partly in elevation, showing a still provided with my improvements;

Fig. 2 a horizontal section on the line $a-b$ in Fig. 1; and

35 Fig. 3 a vertical section of one of the joints of the spreader.

In the drawings like numerals of reference indicate corresponding parts in the different figures.

40 1 is the still, which may be of any form and constructed of any material commonly employed. Usually these stills are made of cast iron.

At the bottom of the still inside I provide 45 a hollow conical spreader supported in any suitable manner and preferably by resting on the bottom of the still. This spreader comprises two parts, the frusto-conical portion 2 and the hollow conical cap 3. The 50 frusto-conical portion 2 has a series of open-

ings 4 formed around its lower edge. Over the opening in its upper end is supported the cap. While any means may be provided for holding the cap in position above the opening and spaced from the sides of 55 the frusto-conical portion 2, I illustrate for this purpose a spider 5 which rests on the part 2 and on the outer ends of which the cap 3 itself rests.

The device, it will be seen, is made in sections, the edges of the sections being halved together. This enables me to introduce the parts through the opening in the top of the still and build up the device inside.

The operation of the device is as follows: 60 The sodium nitrate, which is introduced through the opening 6 in the top of the still, strikes the spreader and is distributed between the spreader and the sides of the still. Part of it will find its way down through the 70 openings 4 into the center of the bottom of the still. A charge of sulfuric acid, when introduced through the opening 6, is distributed by the spreader so that part of it flows over the top of the sodium nitrate and 75 down the inner walls of the still. Part also flows down over the surface of the spreader itself. With this arrangement I find that the acid and sodium nitrate are much more easily and quickly intermingled than when 80 the still is operated in the ordinary way. Normally the sodium nitrate accumulates in a conical heap in the bottom of the still which the acid does not readily penetrate. Gases generated by the acid and sodium nitrate escape readily from the space between 85 the two parts of the spreader.

This device will be found to satisfactorily attain the objects of my invention as set out above in this specification. 90

What I claim as my invention is:—

1. An acid still provided internally at the bottom with a hollow conical spreader provided with inlet openings at its lower edge and a protected gas outlet at its upper end. 95

2. An acid still provided internally at the bottom with a hollow spreader comprising a frusto-conical portion having openings around its lower edge and a conical cap sup- 100

ported over the opening in the top of the frusto-conical portion and spaced from the sides of said portion to form a gas exit.

3. An acid still provided internally at the bottom with a hollow conical spreader divided both vertically and horizontally into sections fitted together, said spreader being provided with inlet openings at its lower

edge and a protected gas outlet at its upper end.

Signed at Parry Sound, Canada, this 22nd day of May 1919.

EDWARD J. MANSER.
